CLAIM

We claim the ornamental design for a cable connector with a grommet and insert, as shown and as described.

DESCRIPTION

FIG. 1 is a top perspective view showing the design; FIG. 2 is a side view of the design shown in FIG. 1; FIG. 3 is a top view of the design shown in FIG. 1; and, FIG. 4 is a bottom view of the design shown in FIG. 1. The broken line portions in the drawings are for illustrative purposes and do not form part of the claimed design. The broken lines represent portions of the structure that forms no part of the claim.

1 Claim, 3 Drawing Sheets
